(57) **CLAIM**

The ornamental design for a golf glove package, as shown and described.

DESCRIPTION

FIG. 1 is a front perspective view of the golf glove package, showing our new design;

FIG. 2 is a side elevation view thereof;

FIG. 3 is a front elevation view thereof; and,

FIG. 4 is a rear elevation view thereof.

The four figures are shown as opaque for purposes of describing more clearly the contours of the design. The actual package will be transparent.
